UNITED STATES PATENT OFFICE.

JOHN T. MEAD, OF CLEVELAND, OHIO, ASSIGNOR TO HIMSELF AND JOHN THOMSON, OF SAME PLACE.

FEED-WATER PURIFIER.

SPECIFICATION forming part of Letters Patent No. 296,203, dated April 1, 1884.

Application filed November 9, 1883. (No model.)

To all whom it may concern.

Be it known that I, JOHN T. MEAD, of Cleveland, in the county of Cuyahoga and State of Ohio, have invented certain new and useful Improvements in Feed-Water Purifiers; and I do hereby declare the following to be a full, clear, and exact description of the invention, such as will enable others skilled in the art to which it pertains to make and use the same.

My invention relates to feed-water purifiers; and it consists in certain features of construction and in combination of parts, hereinafter described, and pointed out in the claims.

15 The object of my invention is to improve a device on which I have already obtained Letters Patent for the United States, dated April 24, 1883, No. 276,189.

In the drawing, the figure is an elevation, 20 partly in section, of my improved feed-water purifier.

A represents the shell of the purifier; B, the boiler; C, the steam-pipe leading from the boiler into the purifier; D, the feed-water pipe leading from the purifier to the boiler, and E the feed-water-supply pipe, leading, usually, 25 from a heater (not shown) to the purifier.

The shell A is provided with two perforated plates, a and a', between which is placed the 30 filtering material, and a hand-hole and plate at a', leading into the filtering-chamber A'.

F is a funnel, the upper edge of which joins the shell A, and is secured thereto, forming a tight joint. The lower end is attached to the 35 pipe f, that extends through the filtering-chamber and into the settling-chamber O. The steam-pipe C is provided inside of the purifier with the conical disks c and c', in the position shown, and has perforations for admitting 40 steam between the conical disks. It will be observed that the discharge of the pipe E is directly over the center of the upper disk.

In operating the device, the live steam, as aforesaid, is admitted through the pipe C be-

tween the conical disks. At the same time the 45 feed-water, usually in a more or less heated condition, is admitted through the tube E, and, falling on the cover c, spreads in a thin sheet over the cover and receives considerable heat from it. As the water passes from the 50 bottom of the cover, it comes in direct contact with the steam, and is thereby heated to the precipitating-point, and, passing through the funnel F and the pipe f, is discharged into the chamber O, when most of the impurities are 55 precipitated, and may be removed through the pipe P. The water then rises through the filtering-chamber, where any floating particles are arrested, and from above the filtering-chamber and below the funnel F the water 60 passes through the pipe D into the boiler.

What I claim is—

1. In a feed-water purifier, the combination of two conical disks, with a steam-pipe arranged to admit steam between the disks, and a feed-water-supply pipe arranged to discharge the feed-water upon the apex of the upper conical disk, substantially as set forth.

2. The combination, with a cylinder divided into two parts by two perforated diaphragms, 70 between which is packed suitable filtering material, the funnel located above the upper diaphragm, and the pipe connected to the funnel and terminating below the lower diaphragm, of the steam-inlet pipe and the conical disks 75 secured thereto, respectively, above and below the escape-openings, the water-supply pipe terminating directly above the center of the upper conical disk, and a water-discharge pipe situated below the upper edge of the funnel, 80 substantially as set forth.

In testimony whereof I sign this specification, in the presence of two witnesses, this 27th day of October, 1883.

JOHN T. MEAD.
